GARMENT AND LAUNDRY PRESSING MACHINE.

Application filed July 5, 1922. Serial No. 573,016.

This invention relates to pressing machines as garment and laundry pressing machines and has for its object a power operated means for applying at least the heavy 5 or final pressure, which means is particularly simple in construction, readily and economically applied to the machine and highly efficient, durable and economical in use, and also which is smooth running and which 10 does not unduly strain the machine. It further has for its object a particularly simple and efficient means for vibrating one pressing member to remove the steam and moisture from the garment or article being 15 pressed. Other objects will appear throughout the specification.

The invention consists in the novel features and in the combinations and constructions hereinafter set forth and claimed.

In describing this invention, reference is had to the accompanying drawings, in which like characters designate corresponding parts in all the views.

Figure 1 is an elevation of one form of machine embodying our invention.

Figure 2 is an enlarged sectional view taken approximately on line 2-2, Figure 1.

Figure 3 is a sectional view on line 3-3, Fig. 2, showing the follower engaged with the cam.

Figure 3^a is a fragmentary view similar to Fig. 3, showing the follower out of engagement with the cam.

Figure 4 is an elevation, parts being 35 omitted, of parts seen in Figure 2 looking from the opposite side of the machine from that shown in Figure 1.

Figure 5 is a view similar to Fig. 3 of another mechanism showing the cam as shiftable instead of the follower.

Figure 6 is a detail view of the operating means for shifting the cam shown in Fig. 5.

This pressing machine comprises generally a frame, pressing members carried by the frame and having relative movement one toward and from the other, means for actuating the movable member comprising a constantly running driving shaft carried by the frame, motion transmitting means between the shaft and the movable member

including driving and driven elements, one of which is shiftable into and out of engagement with the other and means for shifting said shiftable element at will. It 55 also includes a holding means or latch for holding the movable pressing member in down or closed position and arranged to be operated by the power actuated means, and means for releasing the holding means. 60

The actuating means further comprises mechanism by which the movable member may be caused to vibrate to partly open and close the press and thus alternately and momentarily close the press to apply pressure and momentarily partly open the press to slightly separate the pressing members so that the vibrating movement causes the movable pressing member to pound on the garment and also cause a slight alternate sucking and blowing effect, all to remove steam and moisture from the garment, or other article being pressed. 70

The invention is here shown as embodied in a pressing machine of the type shown in 75 patents to A. C. Austin, No. 1,252,988, Jan. 8, 1918, and No. 1,335,151, patented March 30, 1920, in which an upper pressing head is movable toward and from the lower bed or buck mounted on a suitable frame. 80

1 designates the frame which may be of any suitable form, size and construction. The one here shown, includes a suitable table 2 mounted upon front and rear legs 3, 4, there being two front legs 3 and a single rear leg 4, these legs are connected by suitable braces 5. 6 designates the lower pressing element or buck which is mounted upon a standard or what is ordinarily called a goose-neck 6^a which in turn is mounted upon 90 the table 2. 7 is the upper pressing member or pressing head, which is carried by a frame lever 8 pivoted between its ends at 9 to the upward extension or bracket 10 of the rear leg 4, the rear arm of the lever 95 carrying a counterbalance weight 10 and being pivoted at 11 to one end of the toggle link 12, the other end of which is pivoted at 13 to the upper end of a second toggle link 14. This toggle link 14 in the embodiment of the machine here illustrated is pivoted at 15 at its lower end to the frame 100

and is provided with a forwardly extending arm or lever 16 rigid therewith and which when operated, tends to straighten the toggle links 12 and 14, and bring the upper 5 pressing head 7 down toward the lower buck 5. This arm 16 and hence the toggle has heretofore been actuated by a pedal at the front end of the lever 16 and held in its pressing position by a latch 17 having a 10 hook or latching end 18 movable into engagement with a shoulder 19 on the frame and the latch is released by tripping means as a lever 19^a pivoted to the frame and when depressed operating to disengage the latch 15 17 from the shoulder 19 and permit the weight 10 and also an additional counterbalancing spring 20 to open the press or elevate the pressing head 7. The pressing head 7 and lower buck 6 are usually hollow and 20 heated by steam in any suitable manner, unnecessary to describe herein, as steam systems for this purpose are well understood by those skilled in the art.

In addition, the machine is provided with 25 the means for permitting steam to pass from one of the pressing members 5 or 7 usually the lower buck 5, through the garment or article being pressed. This means comprises a valve located within a suitable casing 21, 30 which casing is in communication with the steam system, and means for opening the valve, as a rod 22 connected at its upper end to the valve and at its lower end to any well known operating mechanism.

35 The frame lever 8 which carries the press head 7 is also provided with a suitable handle 25 by which it may if desired be moved by hand toward pressing position preliminary to the application of final or heavy 40 pressure by the operator or by power on the pedal 16.

The power operated means for operating the movable pressing member, that is, the upper pressing head 7 is preferably arranged 45 to apply the final or heavy pressure by moving the toggle links into or about the dead center line of the toggle after the pressing member 7 has been moved preliminarily toward the lower buck 5 and the toggle composed of the links 12, 14 are not quite in a straight or dead center line. However, the power operated means may effect both the preliminary and final pressure movement, but for what might be called "safety first" 50 reasons, it is preferable to effect the preliminary movement of the pressing head 7 by operated actuated means that is, hand or foot operated means rather than wholly by power and using cumbersome guards required by factory laws to prevent the hands 55 of the operator from being caught between the pressing members. Such power operated means comprises a constantly running driving shaft 26, motion transmitting means between the shaft and the movable pressing 60

member, a driving element mounted on and rotatable with the shaft and a driven element mounted on one of the motion transmitting parts, one of said elements being shiftable into and out of engagement with the other and means for shifting the shiftable element at will. This motion transmitting means, in this embodiment of our invention comprises the lever 16, toggle links 14, 12, and frame lever 8, and associated parts. 75

The drive shaft 26 is here illustrated as a shaft driven by an electric motor 27 mounted on the frame, this shaft being journaled in suitable bearings formed on the brace 28 extending between one of the front and rear 80 legs of the frame, the shaft 26 extending transversely of the frame at an angle to the lever 16, and having a worm wheel 29 thereon meshing with the worm 30 on the armature shaft 31 on the motor, which motor is 85 also mounted upon the brace 28 and secured thereto in any suitable manner. The motor, of course, is connected in a feed circuit which is controlled by any suitable switch.

As illustrated in Figure 2, the driving 90 element is a cam 32 mounted on the shaft 26 adjacent the lever 16 and the driven element is a follower 33 carried by the motion transmitting member, as the lever 16, and preferably the follower is shiftable laterally 95 into and out of the path of the constantly rotating cam 32.

In the illustrated embodiment of our invention, as shown in Figures 1, 2 and 3, the follower is mounted on a rock shaft 34 extending lengthwise of the motion transmitting member or lever 16 and journaled in suitable bearings thereon and comprises an arm 35 mounted on said rock shaft 34 to rock therewith and a follower pin 36 carried 105 at the end of the arm, the pin having suitable rollers or other antifriction means 37 thereon. A spring 38 is interposed between the arm and the lever 16 and tends to normally rock the shaft to carry the follower 110 pin out of the path of the cam 32. A pedal 39 is provided on the front end of the shaft to rock the same and also to depress the motion transmitting member or lever 16 to preliminarily actuate the toggle links 14 and 115 12 toward a straight line and effect the preliminary movement of the pressing head 7 toward the lower buck 5.

In the operation, as thus far described, the operator brings the pressing head 7 down 120 toward the lower buck 5 either by pulling downwardly on the handle 25 or depressing the pedal 39 and hence rocking the lever 16 on its pivot 15 and also rocking the shaft and follower 33 against the action of the 125 spring 38.

During such preliminary movement the end of the follower pin 36 abuts the end face of the cam 32 and by so doing, limits the 130 rocking of the shaft so that the pressure ap-

plied to the pedal causes the lever 16 to be depressed. When the pressing head 7 approaches the lower buck 5 the follower pin 36 passes below the low points of the cam so that the pressure on the pedal 39 rocks the shaft to carry the follower pin into the path of the cam. As the cam is constantly rotating when the high point of the cam depresses the follower pin, the lever 16 is depressed bringing the pressing head 7 down into final pressing position and straightening the toggle links and also causing the latch 17 to engage the shoulder 19 and hence hold the press in its closed position, that is, its position occupied when applying heavy pressure. When the latch 17 engages the shoulder 19 as soon as the low point of the cam comes opposite the follower pin, the spring 38 rocks the shaft in the reverse direction and moves the follower pin 36 out of the path of the constantly rotating cam 32. Hence upon the operation of the trip lever 19^a to disengage the latch 17 from the shoulder 19, the press will be opened by the counter-balancing weight 10 and spring 20. However, if upon rocking of the shaft 34 and the depression of the lever 16 by the pedal 39, the trip lever 19^a is also depressed or held tripped, the roller 37 of the follower 36 will be held engaged with the cam 32 by the friction between the cam and the follower and hence the follower will not have opportunity to return to its starting position by the spring 38 for the reason that the latch 17 is held from latching with the hook 19 by the trip pedal which is being held depressed. Hence, the friction between the cam and the follower is not relieved and as the follower remains in engagement with the cam, successive vibrating movements are transmitted to the lever 17, toggle links 14, 12, frame lever 8 and upper press head 7 causing the press head 7 to momentarily separate slightly from the lower buck and article thereon and again momentarily come into pressing relation. Hence, the press is alternately opened and closed, such action continuing until the operator removes his foot from the pedal 19^a and permits the latch to engage the shoulder 19. After the latch has momentarily engaged the shoulder 19 long enough to permit the spring 38 to shift the follower 13 out of the path of the cam 32, the trip lever 19^a is again operated to release the latch permitting the press to open fully. It will be borne in mind that this releasing operation of the follower is due to the fact that the follower and cam are so arranged that there is a clearance between the low points of the cam and the follower pin when the latch 17 is in engagement with the shoulder 19.

This vibrating movement of the movable pressing members or pressing head 7 effects a slapping or pounding on the garment and

also a slight suction and blowing effect which effectively removes the moisture and steam from the garment. The moisture and steam in the garment is that injected into the garment by depressing the lever which opens the steam valve 21 heretofore described. The slapping flattens or smooths out the article better than continuous pressure.

For the purpose of adjusting the follower pin 30 relatively to the cam 32 the follower arm 35 is formed with a transverse bearing 40 and the follower pin 36 is mounted eccentrically in an enlargement 43 mounted in the bearing 40 and held from turning by a set screw 44. By loosening the set screw 44 and turning the part 43, the follower pin 36 and rollers thereon can be adjusted toward and from the working face of the cam.

As seen in Figures 5 and 6, instead of the follower being shiftable, the cam 45 on the constantly movable driving shaft may be shifted by the operator in the movement of the pressing head 7 toward pressing position. In Figures 5 and 6, the cam 45 is slidably mounted on the driving shaft and is actuated by means of the shifter or fork 46 engaging the hub of the cam and actuated through suitable connections 47, 48, and spring 49, between the shifter and the lever 16 or some other motion transmitting part. This connection includes a lever 47 arranged in the path of the lever 16 and motion transmitting part 48, between the lever 47 and the shifter 46. The lever 47 is here shown as having a head 50 arranged in the path of the pedal plate 51 on the front end of the lever 16, the plate having a hole 52 in alignment with the head 50 and through which the head extends as the lever approaches its down position. In operation, the operator places his foot on the plate 51 and depresses the lever 16 to effect the preliminary closing movement of the pressing member 7. Toward the end of the preliminary depressing movement the head 50 of the cam shifting lever 47 enters the hole 52, and the foot of the operator which covers the hole encounters the head 50 and depresses the lever 47 to shift the cam against the returning spring 49 during the latter part of the movement of the lever 47.

Owing to the constantly moving shaft, the operation of the machine is smooth, fast and without jolts and the motor uses a minimum of current.

The degree of pressure is controlled for each class of work by adjusting the toggle in any well known manner.

In the present embodiment of our invention, the link 12 comprises a threaded rod, a thrust bearing or end member 54 at the upper end of the rod and pivoted at 11 to the frame lever 8 and a lower end member or clevis 55 in which the rod is slidably end-

wisely, the end member 55 being pivoted at 13 to the lower toggle link 14. The rod of the link 12 is endwisely movable in the end member or clevis 55 relatively to the link 14 and is yieldingly held from such endwise movement by a spring 56 encircling the rod of the link 12, and thrusting at one end against the upper end of the lower end member 55 and at its upper end against an adjusting nut or wheel 57 threaded on the rod of the link 12 against the upper end of the spring 56. This nut or wheel 57 is locked in its adjusted position by lock nut 58 provided with a suitable handle 59.

15 These machines are primarily intended to be used in clothing factories and laundries, where the operator works for one period upon a certain class of work, all pieces of which require the same amount of pressure, 20 and therefore, the machine can be readily adjusted to the desired pressure by adjusting the toggle by turning the wheel 57; and when another class of work requiring a different pressure is to be operated on, the 25 pressure can be adjusted for that class of work by turning the wheel 57.

This power mechanism is particularly advantageous in that it is readily and economically applied to standard machines, 30 and further in that owing to the constantly running motor, its operation is fast and smooth and is without violent starting and stopping jolts.

Owing to the latch and to the toggle adjustment, the pressure is readily regulated to a predetermined maximum; and further owing to such power mechanism the garment can be readily dried without additional mechanism, or attachments as blowers, or 40 vacuum producing attachments.

What we claim is:

1. In a pressing machine, a frame, pressing members supported by the frame and having relative movement one toward and from the other, means for actuating the movable member comprising a constantly running driving shaft carried by the frame, and motion transmitting means between the shaft and the movable member including a cam element on the driving shaft and a motion transmitting member having a follower element for engaging the cam element, one element being shiftable into and out of engagement with the other, and means for shifting the shiftable element into and out of engagement with the other, substantially as and for the purpose set forth.

2. In a pressing machine, a frame, pressing members carried by the frame and having relative movement one toward and from the other, operator actuated means including a motion transmitting member connected to the movable member for bringing the same toward pressing position, a constantly rotating shaft carried by the frame, a driving

element rotatable with the shaft, a driven element on said motion transmitting member and normally disengaged from the driving element, and means for enabling the shifting of the driven element into engagement 70 with the driving element during the movement of the movable member toward pressing position, said means being controlled by the movement of said operator actuated motion transmitting member, substantially as 75 and for the purpose specified.

3. In a pressing machine, a frame, pressing members carried by the frame and having relative movement one toward and from the other, the movable member having a 80 preliminary movement toward pressing position and a final movement into pressing position, power transmitting means for applying the final pressure movement including a constantly rotating driving shaft carried by the 85 frame, a driving element rotatable with said shaft and a motion transmitting member connected to the movable pressing member to move therewith, a driven element carried by said member, one of said elements being 90 shiftable into and out of engagement with the other and means including a single operating member having an operator engaging part movable in one direction for effecting the preliminary movement of the 95 movable pressing member and movement rotationally relatively to the operating member shifting the shiftable element into engagement with the other element at the end of the preliminary movement, substantially as 100 and for the purpose described.

4. In a pressing machine, a frame, pressing members carried by the frame and having relative movement one toward and from the other, the movable member having a preliminary movement toward pressing position and a final movement into pressing position, power means for applying the final pressure movement including a constantly rotating shaft, a cam element rotatable with the shaft 110 and a motion transmitting member connected to the movable pressing member, a follower element carried by said member for engaging the cam element, said elements being normally disengaged and one being shiftable into and out of engagement with the other, and means for effecting the preliminary movement of the pressing member and shifting said shiftable element into and out of engagement with the other element, substantially 115 as and for the purpose specified.

5. In a pressing machine, a frame, pressing members carried by the frame and having relative movement one toward and from the other, means for actuating the movable member comprising a constantly running shaft carried by the frame, and motion transmitting means between the shaft and the movable member including driving and driven elements, one of which is shiftable 120 130

into and out of engagement with the other, means for shifting said shiftable element at will, a latch mechanism for holding the movable member in pressing position and means 5 for releasing the latch mechanism, said latch mechanism including a part carried by and movable with the motion transmitting means and a part carried by the frame for coacting with the former part, substantially as and 10 for the purpose set forth.

6. In a pressing machine, a frame, pressing members carried by the frame and having relative movement one toward and from the other, means for actuating the movable member comprising a constantly running driving shaft carried by the frame and motion transmitting means between the shaft and the movable member including driving and driven elements, one of which is shiftable into and out of engagement with the other, means for shifting said shiftable element at will, a spring arranged to shift the shiftable element out of engagement with the other element, a latch for holding the movable pressing member in pressing position, and operator actuated means for releasing the latch, substantially as and for the purpose specified.

7. In a pressing machine, a frame, pressing members carried by the frame and having relative movement one toward and from the other, means for actuating the movable member comprising a constantly running driving shaft and motion transmitting means between the shaft and the movable member including a driving element mounted on the shaft and a motion transmitting part connected to the movable pressing member comprising a pedal lever and a driven element carried by the pedal lever and mounted on said lever in position to be carried thereby during the movement of such lever into engagement with the driving element when the movable pressing member approaches the other member, substantially as and for the purpose specified.

8. In a pressing machine, a frame, pressing members carried by the frame and having relative movement one toward and from the other, power means for actuating the movable member comprising a constantly running driving shaft and a motion transmitting means between the shaft and the movable member including a driving element mounted on the shaft and rotatable therewith, a motion transmitting part connected to the movable pressing member comprising a pedal lever and a driven element carried by the pedal lever and mounted on said lever in position to be carried thereby during the movement of such lever into engagement with the driving element when the movable pressing member approaches the other member, and a latch operating to hold

said lever from return movement when such lever has been moved by the power means to carry the pressing member into final pressing position, substantially as and for the purpose set forth.

9. In a pressing machine, a frame, pressing members carried by the frame and having relative movement one toward and from the other, means for actuating the movable member comprising a constantly running 75 driving shaft and a motion transmitting means between the shaft and the movable member including a driving element mounted on the shaft and rotatable therewith, a motion transmitting part connected to the movable pressing member comprising a pedal lever and a driven element carried by the pedal lever and mounted on said lever in position to be carried thereby during the movement of such lever into engagement 80 with the driving element when the movable pressing member approaches the other member, a latch operating to hold said lever from return movement when such lever has been moved to carry the pressing member 85 into final pressing position, and operator actuated means for releasing the latch, substantially as and for the purpose described.

10. In a pressing machine, a frame, pressing members carried by the frame and having relative movement one toward and from the other, means for actuating the movable member comprising a constantly running driving shaft and a motion transmitting means between the shaft and the movable member including a driving element mounted on the shaft, a motion transmitting part connected to the movable pressing member comprising a pedal lever and a driven element carried by the pedal lever and movable during the movement of such lever into engagement with the driving element when the movable pressing member approaches the other member, means for moving the driven element into engagement with the driving element, a latch operating to hold said lever from return movement when such lever has been moved to carry the pressing member into final pressing position, a spring interposed between the lever and the shiftable element to shift it out of engagement with the other element when the latch latches, and operator actuated means for releasing the latch, substantially as and for the purpose specified.

11. In a pressing machine, a frame, pressing members carried by the frame and having relative movement one toward and from the other, means for actuating the movable member comprising a pedal lever pivoted to the frame, a constantly moving drive shaft, a driving element mounted on said shaft, a driven element carried by the lever and movable with the lever into and out of juxtaposition to the driving element, means 125

for moving the driven element into engagement with the driving element, one of said elements being shiftable into engagement with the other when the elements are in juxtaposition and before the lever reaches its final depressed position and means for actuating the pedal lever and moving the driven element into engagement with the driving element substantially as and for the purpose set forth.

12. In a pressing machine, a frame, pressing members carried by the frame and having relative movement one toward and from the other, means for actuating the movable member comprising a pedal lever pivoted to the frame, a constantly moving drive shaft, a driving element mounted on said shaft, a driven element carried by the lever and movable with the lever into and out of juxtaposition to the driving element, one of said elements being shiftable into engagement with the other when the elements are in juxtaposition and before the lever reaches its final depressed position, and a latch for holding the lever in final position and operable by the movement of said lever when said lever has been depressed by the driving element and means for actuating the pedal lever and moving the driven element into engagement with the driving element, substantially as and for the purpose described.

13. In a pressing machine, a frame, pressing members carried by the frame and having relative movement one toward and from the other, means for actuating the movable member comprising a vertically movable pedal lever pivoted to the frame, a shaft carried by the frame at an angle to said lever, a cam element mounted on and rotatable with the shaft adjacent the lever and a follower element carried by the lever in position to move during the depression of the lever into juxtaposition opposite the cam element and one of said elements being shiftable into the path of the other by the movement of the lever toward its lower position and means actuating the pedal lever and moving the driven element into engagement with the driving element substantially as and for the purpose specified.

14. In a pressing machine, a frame, pressing members carried by the frame and having relative movement one toward and from the other, means for actuating the movable member comprising a vertically movable pedal lever pivoted to the frame, a shaft carried by the frame at an angle to said lever, a cam element mounted on and rotatable with the shaft adjacent the lever, a follower element carried by the lever and movable during the depression of the lever into juxtaposition opposite the cam element and one of said elements being carried by and movable with the lever and shiftable into the path of the other with the movement of the

lever toward its lower position, and a latch mechanism coacting with the lever to hold the lever and the movable pressing member in its final or depressed position, said latch mechanism comprising a part carried by the lever and a part carried by the frame, the part carried by the lever being located to engage the part carried by the frame when the lever is depressed by the cam element, substantially as and for the purpose set forth.

15. In a pressing machine, a frame, pressing members carried by the frame and having relative movement one toward and from the other, means for actuating the movable member comprising a lever, a constantly running shaft arranged at an angle to the lever, a cam mounted on the shaft adjacent the lever, a follower carried by the lever and arranged in position to move during the depression of the lever into a position opposite the cam and means for depressing the lever and moving the follower relatively thereto into engagement with the cam, substantially as and for the purpose described.

16. In a pressing machine, a frame, pressing members carried by the frame and having relative movement one toward and from the other, means for actuating the movable member comprising a vertically movable lever pivoted to the frame, a constantly running shaft carried by the frame at an angle to the lever, a cam mounted on the shaft adjacent the lever, a rock shaft extending lengthwise of the lever, a follower including an arm mounted on the rock shaft to rock therewith and a follower pin on said arm and movable by the rocking of the shaft into and out of the path of the cam and means to rock the shaft and depress the lever, substantially as and for the purpose set forth.

17. In a pressing machine, a frame, pressing members carried by the frame and having relative movement one toward and from the other, means for actuating the movable member comprising a vertically movable lever pivoted to the frame, a constantly running shaft carried by the frame at an angle to the lever, a cam mounted on the shaft adjacent the lever, a rock shaft carried by and extending lengthwise of the lever, a follower including an arm mounted on the rock shaft to rock therewith and a follower pin on the arm movable by the rocking of the shaft into and out of the path of the cam, means to rock the shaft and depress the lever and a spring for moving the follower out of the path of the cam, substantially as and for the purpose described.

18. In a pressing machine, a frame, pressing members carried by the frame and having relative movement one toward and from the other, means for actuating the movable member comprising a vertically movable

lever pivoted to the frame, a constantly running shaft carried by the frame at an angle to the lever, a cam mounted on the shaft adjacent the lever, a rock shaft carried by and 5 extending lengthwise of the lever, a follower including an arm mounted on the rock shaft to rock therewith and a follower pin on the arm and movable by the rocking of the shaft into and out of the path of the cam, means 10 to rock the shaft and depress the lever, a spring for moving the follower out of the path of the cam, a latch for holding the lever in the position in which it has been depressed by the cam, and means for releasing 15 the latch, substantially as and for the purpose specified.

19. In a pressing machine, a frame, pressing members carried by the frame and having relative movement one toward and from 20 the other, means for actuating the movable member comprising a vertically movable lever pivoted to the frame, a constantly running shaft carried by the frame, at an angle to the lever, a cam mounted on the shaft adjacent the lever, a rock shaft extending 25 lengthwise of the lever, a follower including an arm mounted on the rock shaft to rock therewith and a follower pin on the arm and movable by the rocking of the shaft into and out of the path of the cam, means 30 to rock the shaft and depress the lever, a spring for moving the follower out of the path of the cam, a latch for holding the lever in the position by which it has been depressed by the cam, and means for releasing 35 the latch and for holding the latch out of operative position whereby the follower pin remains in engagement with the cam due to frictional engagement and pressure between 40 the cam and the follower pin, substantially as and for the purpose set forth.

20. In a pressing machine, a frame, pressing members carried by the frame and having relative movement one toward and from 45 the other, means for actuating the movable member comprising a constantly running driving shaft carried by the frame, a motion transmitting means between the shaft and the movable member comprising an operator 50 actuated part, a cam element mounted on the shaft, a follower element on said part, one of said elements being shiftable into and out of engagement with the other, a spring 55 to move the shiftable element out of engagement position and means associated with said part for shifting the shiftable element into engagement with the other element during 60 the operation of said part by the operator, substantially as and for the purpose described.

21. In a pressing machine, a frame, pressing members carried by the frame and having relative movement one toward and from the other, means for actuating the movable

member comprising a constantly running 65 driving shaft carried by the frame, a motion transmitting means between the shaft and the movable member comprising an operator actuated part, a cam element mounted on the shaft, a follower element on said part, 70 one of said elements being shiftable into and out of engagement with the other, a spring to move the shiftable element out of engagement position, means associated with said part for shifting the shiftable element 75 into engagement with the other element during the operation of said part by the operator, a latch mechanism for holding the operator actuated part in its depressed position after said elements have been engaged, 80 said latch mechanism comprising coacting parts carried respectively by the operator actuated part and a part carried by the frame, said parts of the latch mechanism being arranged to engage when the cam 85 finally depresses the operator actuated part and means for releasing the latch, substantially as and for the purpose specified.

22. In a pressing machine, a frame, pressing members carried by the frame and having relative movement one toward and from the other, means for actuating the movable member comprising a constantly running driving shaft carried by the frame, a motion transmitting means between the shaft and the movable member comprising an operator actuated part, a cam element mounted on the shaft, a follower element on said part, one of said elements being shiftable into and out of engagement with the other, a spring to move the shiftable element out of engagement position, means associated with said part for shifting the shiftable element into engagement with the other element during the operation of said part by the operator, a latch 90 for holding the operator actuated part in its depressed position after the said elements have been engaged and means for releasing the latch, said releasing means being operable to hold the latch from operation and thereby holding the follower and cam in engagement due to the friction and pressure between said elements, substantially as and for the purpose set forth. 100

23. In a pressing machine, a frame, cooperating pressing members supported by the frame and having relative vertical movement, one toward and from the other, means for actuating the movable member comprising a drive shaft carried by the frame and motion transmitting means between the shaft and the movable pressing member including two parts normally out of engagement and a vertically movable support, one of said two parts being carried by and movable in a vertical direction with the support and arranged to be brought at the end of the vertical movement of the support into 110 115 120 125

juxtaposition with the other of said two parts and an operating member carried by the vertically movable support and having a movement relatively thereto and connected to one of said two parts to move the same into engagement with the other of said two parts at the end of the vertical movement, the operating member having an operator engaging part movable rotationally relatively to said support. 10

In testimony whereof, we have hereunto signed our names at Syracuse, in the County of Onondaga, and State of New York, this 1st day of July, 1922.

ALBERT B. CLISSON.
PHILIP N. BRAUN.
